J. W. F. MACDONALD,

HEATER SYSTEM.

APPLICATION FILED DEC. 5, 1918.

1,437,187.

Patented Nov. 28, 1922.

John W. F. Macdonald.

By
Henry J. Miller
Atty.

UNITED STATES PATENT OFFICE.

JOHN W. F. MACDONALD, OF BRIGHTON, MASSACHUSETTS, ASSIGNOR TO THE MERRILL PROCESS COMPANY, A CORPORATION OF MASSACHUSETTS.

HEATER SYSTEM.

Application filed December 5, 1918. Serial No. 265,385.

To all whom it may concern:

Be it known that I, JOHN W. F. MACDONALD, a citizen of the United States, and a resident of Brighton, in the county of 5 Suffolk and State of Massachusetts, have invented an Improved Heater System, of which the following is a specification, reference being had to the accompanying drawings, forming part thereof.

10 This invention has reference to an improvement in the class of heating systems of the type disclosed in my prior Patent No. 1,278,067 granted September 3, 1918, in which a heat absorbing oily liquid is mechanically circulated through a continuous 15 conduit having a point of heat utilization or radiation and a point of heat absorption. At such point of radiation said liquid may contract somewhat through loss of heat after 20 which said liquid passes to a pump at the suction side of which deficiencies in volume are compensated for by a supply of liquid from an expansion pipe. In the passage of said liquid through the pump it is subjected 25 to the mechanical pressure of said pump and passes to the heating point under said pressure. At such heating point said liquid is subjected to a high temperature and its globules or bubbles tend to expand and such 30 expansion is increased by the pressure of any air or humidity present in the conduit by reason of condensation or by water or air inadvertently entering with the supply of oil from the expansion pipe.

35 The main object of this invention is to provide a vent for the escape of air, water or gas of any kind from the circulating liquid of systems of this nature approximately at the time when said liquid is at its 40 greatest expansion and is under pressure of the circulating pump. That is, air, moisture or other gas inadvertently entering the conduit from the expansion tank or present in liquid in such conduit at the heating point 45 should be eliminated or, at least, allowed to escape before such air, moisture, etc., causes an undue or possibly dangerous expansion of the circulating liquid.

The invention consists in the novel features of construction and combination of parts as shall hereinafter be more fully described and pointed out in the claims.

The drawing represents a view in elevation of a heating system of the nature herein

referred to and illustrating the new improvement.

As shown in the drawing 5 indicates a furnace of any known construction having the coil conduit 6 of any well known kind adapted to direct the flow of liquid passing therethrough to facilitate the absorption by said liquid of heat supplied to said furnace. At a distance from said furnace coil 6 is located the radiator conduit 7 which is the point or device at which the heat absorbed by the liquid in passing through the coil 6 is utilized. Such liquid is conveyed from the coil 6 to the coil 7 by an upper supply conduit 8 and after the heat of said liquid has been wholly or partially utilized in 70 said coil 7 said liquid is returned to coil 6 through a lower return conduit 9.

The system, therefore, comprises in circuit a heater, a heat utilizing means, a supply conduit leading from said heater to said heat utilizing means, and a return conduit leading from the latter to the heater, all of which are filled with a fluid normally of a viscous nature having a high sparking point. This circulating liquid is maintained at a 80 temperature below its boiling point whereby generation of gaseous vapor is avoided. In order to effect the circulation of the liquid, the return conduit 9 is provided with mechanically operated means, preferably a 85 pump, for producing a forced mechanical circulation of the liquid through the entire circuit and being located in the return section 9 of the conduit, said pump subjects the cooler, and somewhat condensed, liquid 90 to a sufficient mechanical pressure to maintain a free circulation thereof toward the heater. The action of the pump also causes the free circulation of the heated liquid from the heater to the radiator or other heat utilizing means.

In order to compensate for the fluctuations of the liquid in the return conduit 9 by the suction of the pump, and to maintain a static pressure upon the liquid throughout 100 the entire circulating system, the conduit 9 is provided at a point preferably near the suction end of the pump 10 with a pipe 11 which communicates at its upper end with an expansion tank 12 preferably located at 105 a higher level than the supply conduit 8. The supply conduit 8 is provided with a branch or vent pipe 13 which extends up-

wardly and communicates with the upper end of the expansion tank 12, and is adapted to afford a passage for the air or gas which is generated from or accumulates in the 5 circulating liquid. It also provides means whereby a small amount of the circulating liquid may be by-passed from the supply conduit 8 into the expansion tank. The union which connects the supply conduit 8 with the 10 branch or vent pipe 13 desirably is of considerably greater diameter than that of the conduit 8 and forms a chamber or trap 8* for the air or gas which is contained in the circulating fluid.

15 It has been found in starting a newly installed system of this nature that the liquid with which the conduit system is filled contains considerable air, moisture and accumulations of liquid of a more volatile nature than the main body of liquid. Under heat, such air, moisture and more volatile liquid expand and often cause undue expansion of the main liquid which reduces the efficiency of the system, particularly the 20 pump. In practice it is found that in starting a new system the valve 14 of branch or vent pipe 13 may be left open for the escape of air, steam or other gas for a considerable period, sometimes for several 25 days, without permitting the escape of any material amount of the viscous circulating liquid through such pipe 13 of small diameter.

When the system is out of operation, as 30 for instance, overnight, the mechanical circulation of the viscous liquid ceases and the temperature of said liquid usually is reduced whereby said liquid may contract or become somewhat condensed. In such variations in the density of the liquid and 35 possibly for other reasons, bubbles are formed in the liquid and small amounts of air or water find their way into the body of the liquid, and other impurities contained in said liquid may coalesce to an objectionable extent. It is of course desirable to discharge such air or gas and other impurities from the liquid particularly at the 40 starting of the system or soon thereafter.

45 50 Without considering specific details of the operation of the system it may be observed that the application of heat to the coil 6 effects a rise in temperature of the liquid contained in said coil and a resultant expansion of said liquid and particularly of the moisture, air or other gas contained therein whereby if a vent is opened said moisture, air or other gas with the bubbles or globules of liquid containing said moisture will tend to escape through said vent.

The operation of pump 10 forces the liquid in return conduit 9 towards and through the coil 6 from which the heated liquid, expanded by the heat applied to said 55 coil 6, enters the supply conduit 8 and

passes by the vent pipe 13 through which, if valve 14 is open, the more volatile or lighter portions of gas escape, passing upward through said pipe 13 and ultimately reaching the expansion tank 12. The 70 heavier or more viscous liquid circulates through said supply conduit 8 to and through the radiator coil 7 and thence through the return conduit 9 to the pump 10 and may, through loss of heat, again contract or condense and sometimes permit the formation of additional bubbles. At or about the time such liquid reaches the suction side of pump 10, the fluctuations in 75 density and volume of said liquid are, to a large extent compensated for by liquid from the expansion pipe which liquid is under static pressure.

80 By locating the outlet of vent pipe 13 at a considerably higher point than the inlet to said pipe 13 from the conduit arm 8 and making said vent pipe considerably smaller than conduit arm 8 resistance is provided to the passage of the main body of viscous liquid through said pipe 13.

85 Having thus described my invention I claim as new and desire to secure by Letters Patent.

90 95 100 105 110 115 1 A heating apparatus for transporting heat by means of a traveling body of viscous material maintained at a temperature below its boiling point, comprising in a circuit a heater, a heat utilizing means, a supply conduit leading from said heater to said heat utilizing means, a return conduit leading from said heat utilizing means to said heater, a pump in the return conduit acting to circulate the liquid in said conduit toward said heater, an expansion tank located at a higher level than said supply conduit, means for delivering liquid from said expansion tank to the return conduit upon the intake side of said pump adapted to maintain a constant static pressure upon the liquid throughout the circuit, a chamber in said supply conduit adapted to trap and separate gaseous impurities or products from the circulating liquid and a vent pipe communicating with the upper portion of said chamber to permit the escape 115 of such gaseous impurities or products.

120 125 130 2. A heating apparatus for transporting heat by means of a travelling body of viscous liquid maintained at a temperature below its boiling point, comprising in circuit a heater, a heat utilizing means, a supply conduit leading from said heater to said heat utilizing means and a return conduit leading from the latter to said heater, mechanically operated means for circulating the liquid in the return conduit towards said heater, an expansion tank, means for delivering liquid therefrom to said return conduit between said heat utilizing means and said circulating means adapted to main- 130

tain a static pressure on said liquid throughout the circuit, a chamber in said supply conduit adapted to separate gaseous impurities or products from the circulating liquid, and a branch pipe connecting said chamber with said expansion tank, and a valve in said branch pipe operable either to

permit the delivery of the gaseous impurities and a portion of the liquid circulating through said supply conduit to said expansion tank or to confine the circulating fluid to said conduit. 10

JOHN W. F. MACDONALD.
